UNITED STATES PATENT OFFICE.

CHARLES A. ENSIGN, OF NAUGATUCK, CONNECTICUT, ASSIGNOR TO GOOD-YEAR'S METALLIC RUBBER SHOE COMPANY, OF SAME PLACE.

DESIGN FOR OVERSHOES.

SPECIFICATION forming part of Design No. 11,821, dated June 15, 1880.

Application filed May 3, 1880. Term of patent 3½ years.

To all whom it may concern:

Be it known that I, CHAS. A. ENSIGN, of Naugatuck, in the State of Connecticut, have invented a new Design for Overshoes; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for india-rubber overshoes; and it consists in the peculiar cut or shape of the upper edge, as shown in the accompanying illustration.

The upper edge, starting from the center at the heel, runs forward, curving downward to the shank, thence, substantially parallel with the sole, to near the toe, thence inward and backward, and terminating in a transverse line across a tongue-piece, *a*, at the top, as

shown in the accompanying illustration. On the side of the shoe, from the heel to the shank, is an ornamented scroll-work made in imitation of stitching, and also scroll-work ²⁵ springing from the tongue-piece forward at the toe, and transverse ribs with imitation of holes and lacing at the toe, as shown.

I claim—

The design for overshoes, consisting of the configuration of the upper edge, starting from the center at the heel, running downward to the shank portion, thence forward, substantially parallel with the sole, to near the toe, there curved inward and backward, terminating ³⁵ in a transverse line across the tongue-piece *a* on the top.

CHAS. A. ENSIGN.
